Patented May 20, 1919.

Fig. 1.

UNITED STATES PATENT OFFICE.

LYMAN C. DAVIDSON, OF CHICAGO, ILLINOIS.

ADJUSTABLE RETAINER FOR CIGARS IN BOXES.

1,304,266.

Specification of Letters Patent.

Patented May 20, 1919.

Application filed March 19, 1917. Serial No. 155,682.

To all whom it may concern:

Be it known that I, LYMAN C. DAVIDSON, a citizen of the United States, residing at Chicago, in the county of Cook and State 5 of Illinois, have invented a certain new and useful Improvement in Adjustable Retainers for Cigars in Boxes, of which the following is a specification.

This invention is a device for retaining 10 any number of cigars, less than the number required to fill a cigar box, in position in the box so that they are not broken by being shaken around in the box as it is moved about either in the cigar store where the 15 goods are sold or by being carried in the pocket or in a vehicle.

The object of the invention is to provide 20 a device for this purpose, which can be easily made and readily applied to and removed from the cigar box without in any way injuring the contents thereof.

The invention consists generally in detachable means bodily insertible in the cigar box for retaining the cigars in position, the 25 same being flexible so as to accommodate itself to any number of cigars from one up which may be in the box. The invention consists more particularly in the features and details of construction hereafter more 30 fully set forth in the specification and claim.

Referring to the drawings, in which similar numerals indicate the same parts throughout the several views,

Figure 1 is a plan view of the cigar box 35 having a quantity of cigars less than the capacity of the box retained in position by the device of this invention.

Fig. 2 is an end view of the cigars and securing mechanism shown in Fig. 1 taken 40 just inside the lower side wall shown in Fig. 1.

Fig. 3 is a detail view illustrating the 45 form of operating mechanism for attaching the device to the box employed at the left end of the pile of cigars of Figs. 1 and 2.

Fig. 4 is the alternative and preferred 50 form of mechanism for accomplishing the same result as that of the device of Fig. 3, it being the mechanism employed at the right end of the cigars of Figs. 1 and 2.

Fig. 5 is a detail view partially in section through the right hand end of the mechanism illustrated in Fig. 4.

Fig. 6 is a detail view partially in section

through the left hand end of the mechanism 55 of Fig. 4.

Fig. 7 is a changed position view of the parts illustrated in Fig. 5.

The specific embodiment of the invention illustrated in the drawings is especially de- 60 signed for application to an ordinary wooden cigar box having side walls 10, end walls 12, a bottom 14, and a cover 16. The device might, however, be applied to boxes of other materials without departing from 65 this invention.

When part of the cigars 17 in a box have been removed, it is necessary, if the box with the remaining cigars are to be transported, that some device be provided for tightly se- 70 curing the remaining cigars in compact position so that they will not be broken. The device of this invention, broadly speaking, accomplishes this result by providing one or a plurality of flexible, usually elastic, bands 75 20 extending over the cigars in the box and attached at their opposite ends to removable supports 22 and 24 inserted across the box in any desired position. The more particu- 80 lar features of this invention relate to 80 means for securing these rigid supports 22 and 24 in selected positions along the side walls 10 of the cigar box.

In the particular form of securing mechanism illustrated in the left half of Fig. 1, 85 the rigid member 24 is provided on one end with an enlargement 26 in which a needle 28 is screw-threaded at 30, as shown in detail in Fig. 6, and at the other end with a corresponding enlargement 32 in which a 90 needle 34 is reciprocatably mounted. The needle 28 may be detachably secured in adjusted position by a lock nut 36. The needle 34 is reciprocated by the operation of two toggle links 38 and 40, link 38 being pivoted 95 to needle 34 at 42 and to link 40 at 44, the latter link 40 being journaled on a fixed pivot pin 46 on rigid member 24. The toggle device 38-40 is prevented from movement too far across rigid member 24 by a 100 stop 48.

The mechanism just described is of such a size and proportion that when the parts are in the position shown in Fig. 3, with the needle 34 drawn into member 32, the de- 105 vice can be placed in any position crosswise of the box between the walls 10, and that when the toggle device 38-40 is then moved

from the position of Fig. 3 until link member 40 touches stop 48, the two pins 28 and 34 will be driven into engagement with the comparatively soft walls 10 of the box, thus 5 definitely positioning the device of Fig. 3 with reference to the box and the cigars therein. The mechanism of Fig. 3 just described can, if desired, be used at both ends of the pile of cigars without departing from 10 this invention.

The preferred form of mechanism illustrated at the right hand end of the pile of cigars, Fig. 1, is applied to rigid support 22. This latter support is provided at one end 15 with the parts 26, 28, 30 and 36 identically like those heretofore described. At the opposite end of this member 22 is an enlargement 50 in which locking pin 52 is reciprocable in the same manner that pin 34 moves 20 in member 32. The outer end of this pin 52 is provided with a sharp point 54 adapted to readily enter the material of a side wall 10 of the cigar box, while the opposite end of the pin is provided with a right angularly 25 bent portion or lug 56 entering and traveling in an elongated slot 58 cut in the adjacent portion of rigid member 22. Pivoted to member 22 at 62 is a locking lever 64 having formed in it a cam slot 66 inclosing member 30 or lug 56 on pin 52. This cam slot 66 is so shaped and arranged that when the parts are in the position shown in Fig. 5, the pin 52 is drawn into member 50, and that when the lever 64 has been moved through the 35 position of Fig. 7 to a position in which lever 54 is in alinement with member 22, the pin 56 will be projected from member 30 sufficiently so that pins 28 and 52 will be driven into the walls 10 of the cigar box, as 40 clearly appears in Fig. 1.

The members 26, 32 and 50 are provided with loops 70 under which the bends 20 pass, as shown, in the process of assembling the parts, thereby preventing removal of the 45 bands from the device when the rigid supporting members 22 and 24 are removed from a particular cigar box.

While the device has been shown and described as applicable to a wooden cigar box, 50 it is obvious that if a metallic cigar box have

its walls corresponding to walls 10 indented or completely perforated, the device can be applied and used in such a box.

In the practical operation of the device, member 24 and its attached parts will ordinarily be inserted in position across the cigar box, as shown in Fig. 1, and left there for an indefinite time while the operator will, 55 reposition the member 22 from time to time, as the removal of cigars 17 from the box may 60 require. The elastic bands 20 should ordinarily be so constructed that a limited number of cigars may be removed from underneath these elastic bands without its being necessary to remove and reposition the member 22. In repositioning this member 22, the operator obviously moves the lever 64 to the position shown in Fig. 5 to remove the member 22, and after replacing that member 65 in its new position locks it there by moving the lever 64 through and beyond the position of Fig. 7 to that shown at the right hand end of Fig. 1, as heretofore described. 70

Having thus described my invention, what I claim as new and desire to secure by Letters Patent, is:— 75

A device for securing loose articles in a receptacle comprising a flexible retaining member, anchor members carried at the ends of the flexible member respectively, one of 80 said anchor members including a body, having means at one end for engagement with one wall of a receptacle, a longitudinally reciprocating pin carried at the other end of the body for engagement and disengagement 85 with and from an opposite wall of a receptacle, a lateral extension on said pin movable in a longitudinal slot in the body, and an operating lever pivoted to the body and having a cam slot receiving the lateral extension 90 whereby the movement of the lever will reciprocate the pin.

In witness whereof, I have hereunto subscribed my name in the presence of two witnesses.

LYMAN C. DAVIDSON.
